(57) **CLAIM**

The ornamental design for a cosmetic tube, as shown and described.

DESCRIPTION

FIG. 1 is a front elevation view of a cosmetic tube.

FIG. 2 is a rear elevation view of the cosmetic tube of FIG. 1.

FIG. 3 is a left side elevation view of the cosmetic tube of FIG. 1.

FIG. 4 is a right side elevation view of the cosmetic tube of FIG. 1.

FIG. 5 is a top plan view of the cosmetic tube of FIG. 1.

FIG. 6 is a bottom plan view of the cosmetic tube of FIG. 1; and,

FIG. 7 is a front, right, top perspective view of the cosmetic tube of FIG. 1.

The broken lines in the drawings depict portions of the cosmetic tube that form no part of the claimed design.

1 Claim, 7 Drawing Sheets
